ATTORNEY

UNITED STATES PATENT OFFICE.

ADIEL Y. DODGE, OF SOUTH BEND, INDIANA, ASSIGNOR TO BENDIX BRAKE COMPANY,
OF CHICAGO, ILLINOIS, A CORPORATION OF ILLINOIS.

BRAKE SHOE.

Application filed October 4, 1926. Serial No. 139,388.

This invention relates to brakes and is illustrated as embodied in an internal expanding automobile brake. An object of the invention is to provide a novel construction of the shoe or shoes used in the brake, especially in providing constructions suitable for use in brake shoes made of steel stampings.

Among the features of novelty which add to the utility of these shoes, especially when they are made of stampings, are an arrangement of a U-section thrust member at one end of the shoe having its sides fitting between and secured to spaced stiffening webs forming part of the shoe; novel pivot bushings having flanges and retainers arranged to grip opposite faces of the parts of the webs forming the pivot arms of the shoe; and a shoe construction including a segmental cylindrical outer band reinforced by spaced members secured to its inner face and forming a pair of arcuate webs so arranged as to give a generally channel-shaped shoe. Preferably these spaced stiffening members have narrow outer cylindrical flanges engaging and secured to the inner face of a band adjacent its side edges and preferably flush at their outer edges with the side edges of the band.

The above and other objects and features of the invention, including various novel and desirable details of construction, will be apparent from the following description of one illustrative embodiment shown in the accompanying drawings, in which:

Figure 1 is a vertical section through the brake, just inside the head of the brake drum, showing the novel brake shoes in side elevation;

Figure 2 is a partial section on the line 2-2 of Figure 1, showing the anchorages of the shoes;

Figure 3 is a section through the central shoe on the line 3-3 of Figure 1;

Figure 4 is a section through one of the end shoes on the line 4-4 of Figure 1; and

Figure 5 is a partial inside plan view of one of the end shoes on the line 5-5 of Figure 1.

In a general way, the brake selected for illustration includes a rotatable drum 10 closed at its open side by a suitable stationary backing plate or equivalent support 12 and within which are arranged three brake shoes 14, 16, and 18. Shoe 14 is anchored

on a pivot 20 carried by backing plate 12, and shoe 16 is anchored on a pivot 22 also carried by the backing plate. Shoe 18 is connected to the unanchored end of shoe 16 by a suitable floating pivot 24. The brake is applied by means such as a double cam 24 forcing the shoes 14 and 18 apart against the drum against the resistance of a return spring 28, whereupon shoe 18 applies shoe 16 against the resistance of an auxiliary return spring 30.

The present invention relates to the construction of the brake shoes, the general organization of the brake being substantially as covered by my prior applications and patents. In a general way the end shoes 14 and 18 are of channel section (see Figure 4), while shoe 16 is T-shaped in section (see Figure 3).

Each of the end shoes 14 and 18 is built up of three principal parts, viz, an outer segmental cylindrical band 32 which is shown as carrying the brake lining 34, and two stampings 36 and 38 forming spaced stiffening webs for the shoe and which are shown as being channel-shaped to provide inner stiffening flanges 40 and outer flanges 42 which engage and are secured to the inner face of the band 32 adjacent its side edges. Preferably flanges 42 are flush at their outer edges with the side edges of the band 32. If preferred, the stampings may be brought somewhat closer together at the end of each of the shoes next the cam 26 or its equivalent so that they are spaced apart the proper distance to receive the side portions of a U-section thrust member 44 fitting between and secured to the stampings.

At the pivoted ends of the shoes 14 and 18 the stampings are shown projecting beyond the ends of the bands 32 to form spaced pivot arms which preferably converge to positions immediately adjacent the opposite sides of the shoe 16 (see Figure 2). Each of the pivot arms formed by the projecting and inwardly offset end of one of the stampings is provided with a pivot bearing shown as a bushing having a flange 46 engaging one face of the stamping and a bearing portion 48 extending through an opening in the stamping and on which is sleeved a retaining member 50 engaging the opposite face of the stamping and held by spinning or distorting the end of the bearing portion 48 over its outer face at 52 to form an integral rivet 110.

connection. The pivots 20 and 24 are received in the bushings thus formed.

The shoe 16 is shown as built up of a segmental cylindrical band 54 shown as carrying the lining 56 and which is reinforced by two L-section stampings 58 spot-welded or otherwise secured back to back and secured to the inner face of the band. The stampings have inner stiffening flanges 60 corresponding to the flanges 40 and outer flanges 62 which are preferably flush at their outer edges with the opposite side edges of the band 54. At its ends, where it receives the pivots 22 and 24, the shoe is formed with bearings for those pivots each including a bushing 64 having a flange 66 engaging one face of the stiffening web made up of the two stampings, and having a bearing portion 68 which projects through an opening in the web and on which is sleeved a retaining member 70 engaging the opposite face of the web and held by an integral rivet portion 72.

While one illustrative embodiment has been described in detail, it is not my intention to limit the scope of the invention to that particular embodiment or otherwise than by the terms of the appended claims.

I claim:

- 30 1. A brake shoe having spaced portions at least at its end, in combination with a U-section thrust member having its sides fitting between and secured to the inner faces of said portions.
- 35 2. A channel-shaped brake shoe having spaced side flanges in combination with a U-section thrust member having its sides fitting between and secured to the inner faces of said portions at one end of the shoe.
- 40 3. A brake shoe built up of three principal parts, viz: a segmental cylindrical outer band, and a pair of spaced stiffening members, each including an arcuate web portion and a narrow cylindrical flange engaging and secured to the inner face of the band adjacent one of its side edges.
- 45 4. A brake shoe built up of three principal parts, viz: a segmental cylindrical outer band, and a pair of spaced channel-sec-

tion stiffening members, each including an arcuate web portion and an outwardly-extending narrow cylindrical flange engaging and secured to the inner face of the band adjacent one of its side edges and flush at its edge with said side edge.

5 5. A brake shoe built up of three principal parts, viz: a segmental cylindrical outer band, and a pair of spaced stiffening members, each including an arcuate web portion and a narrow cylindrical flange engaging and secured to the inner face of the band adjacent one of its side edges, said stiffening members extending beyond the end of the band as spaced pivot arms offset substantially within the curve of said band.

6 6. A brake shoe having at its end a stiffening web formed with an opening in combination with a pivot bushing having a flange engaging one face of the web and a bearing portion projecting through the opening, and a reinforcing and retaining member sleeved on said bearing portion and engaging the opposite face of the web.

7 7. A brake shoe having at its end a pair of spaced stiffening webs formed with coaxial openings in combination with a pair of pivot bushings having flanges engaging the faces of the webs and bearing portions projecting through the openings, and reinforcing and retaining members sleeved on said bearing portions and engaging the opposite faces of the webs.

8 8. A brake shoe having at its end a pair of spaced stiffening webs formed with coaxial openings in combination with a pair of pivot bushings having flanges engaging the faces of the webs and bearing portions projecting through the openings, and reinforcing and retaining members sleeved on said bearing portions and engaging the opposite faces of the webs, the end of the bearing portion being displaced over the outer face of the retaining member to hold it in place.

In testimony whereof, I have hereunto signed my name.

ADIEL Y. DODGE.
